United States Patent Office

Des. 192,980
Patented June 5, 1962

192,980

DUAL COMPARTMENT BOTTLE

John Mangini, Whitestone, N.Y., and Roscoe G. Reed,
Owings Mills, Md., assignors to Clairol Incorporated,
New York, N.Y., a corporation of Delaware

Filed May 3, 1961, Ser. No. 65,014

Term of patent 14 years

(Cl. D58—6)

Fig. 2.

Fig. 4.

Fig. 1.

Fig. 3.

FIG. 1 is a front elevational view of a dual compartment bottle showing our new design;

FIG. 2 is a top plan view;

FIG. 3 is a side elevational view; and

FIG. 4 is a cross sectional view thereof, taken on the line 4—4 of FIGURE 1.

The bottom is plain and unornamented and the rear and side not shown are the same in appearance as the respective front and side shown.

We claim:

The ornamental design for a dual compartment bottle, as shown and described.
